UNITED STATES PATENT OFFICE.

VICTOR ODQUIST, OF YONKERS, NEW YORK, ASSIGNOR TO AMERICAN CAN COMPANY, OF NEW YORK, N. Y., A CORPORATION OF NEW JERSEY.

REENFORCED-METAL SPOOL.

Application filed October 8, 1921. Serial No. 506,247.

To all whom it may concern:

Be it known that I, VICTOR ODQUIST, a citizen of the United States, residing in Yonkers, in the county of Westchester and State of New York, have invented a new and useful Improvement in Reenforced-Metal Spools, of which the following is a specification.

This invention relates in general to spools such as are used in winding silk thread and the like, and has more particular reference to reenforced metal construction of a spool for this general purpose.

It has heretofore been the custom to use wooden spools having comparatively thick core or barrel parts, for the purpose stated, since no other type of construction was known which provided sufficient strength at practicable cost.

A principal object of my invention is the provision of a metal reenforced spool of strength equal or superior to that of the wooden spools heretofore used, and constructed in such manner as to be capable of being produced at low cost and without the employment of expensive material or machinery.

In metal spools heretofore tried for use in this connection difficulty has been experienced not only in the foregoing particulars, but in having the thread become packed in between the barrel and end portions of the spool. It is, therefore, a further object of my invention to provide a spool in which the parts mentioned are secured together in such manner as to overcome this difficulty, while at the same time being of the required strength and cheapness.

Numerous other objects and advantages of the invention will be apparent as it is better understood from the following description, which, taken in connection with the accompanying drawings, discloses a preferred embodiment thereof.

Referring to the drawings,

Figure 1 is a side elevation of a reenforced metal spool constructed in accordance with my invention, a portion thereof being shown in section;

Fig. 2 is a plan view of an end thereof;

Fig. 3 is a vertical section taken through a portion thereof, the end parts being shown in separated relation; and

Fig. 4 is an enlarged section taken substantially on the line 4—4 in Fig. 1.

Upon the drawings which illustrate a preferred embodiment of the invention, the reference character 11 indicates a sheet metal barrel or core which is tubular in form and has its side edges joined in an internal lock seam indicated generally by the reference character 12. This seam is formed by turning the material of the barrel back upon itself as at 13, and returning the part beyond the bend 13 back as at 14, and forming the extremity thereof into a hook 15. This hook is engaged by an oppositely disposed hook 16 in the other side edge. Metal end members 17 are formed with internal outwardly extending flanges 18 adapted to be slipped upon the straight walls 19 at each end of the barrel portion 11. These members have also an exterior upstanding flange 21, a channel 22 being formed between said flanges. A beaded metal reenforcing member 23 is positioned in the channel 22 and the outer flange 21 is turned down thereon as at 24. The end members are slipped well upon the barrel walls and the extremities of said walls are flanged as at 25 and turned into locking engagement with the inner flange 18, the extremity 26 of which is also turned outwardly and embraced in a seam with the flange 25. It will be observed that the extremity of the flange 25 bears upon the inner part of the reenforced member 23, which is held thereby and by the flange 24 in firmly fixed position. The flange 18 fits snugly upon the wall 19 and particularly when interlocked with the flange 25 is so firmly positioned as to prevent entrance of threads between it and said barrel wall, thereby preventing the packing of threads between these parts and obviating the defect in this regard which has existed in other types of metal spools. It will be noted also that with the flanges of the various parts formed as described, the spool presents no sharp points or edges since all of the exposed parts are suitably rounded and protected. Furthermore, with the tight seams provided and the firm positioning of the beaded or corrugated reenforcing member 23, a strong and efficient construction is obtained. The entire spool is formed from a single type of metal, preferably sheet metal, and of few parts, which

may be readily stamped and formed with ordinary machinery, and with few and simple operations. Thus, it will be seen that I have provided a strengthened, efficient and 5 economical metal spool thoroughly adapted for the purposes above set forth.

It is thought that the invention and many of its attendant advantages will be understood from the foregoing description, and 10 it will be apparent that various changes may be made in the form, construction and arrangement of the parts without departing from the spirit and scope of the invention or sacrificing all of its material advantages, 15 the form hereinbefore described being merely a preferred embodiment thereof.

I claim:

1. In a reenforced sheet metal spool, the combination of a tubular barrel, end members fitting around the barrel at the ends thereof, and reenforcing members whereby the end flanges of the spool are made of double thickness, the outer margins of the reenforcing members and end members being interlocked in peripheral seams, and the inner margins of the reenforcing members,

the end members and the end edges of the barrel being interlocked in seams at the ends of the barrel.

2. A sheet metal spool comprising, in combination, the following elements; a sheet metal tubular barrel, sheet metal annular end members and sheet metal annular reenforcing members, the end members being of channel formation having inner and outer 30 flanges which are bent respectively outward and inward over the edges of the reenforcing members, and the end edges of the barrel being bent outward over the reenforcing members and interlocked under the edges of 35 the inner flanges of the end members.

3. In a sheet metal spool, in combination, a sheet metal tubular barrel member and annular end members, the end members having flanges resting against the barrel member at the ends thereof and having the extremities of said flanges bent outward, and the edges of the barrel member being bent inward under the said flanges, and reenforcing members united with said barrel and end 40 members. 45

VICTOR ODQUIST.
